FILING CABINET

Filed April 6, 1931

INVENTOR.
Robert W. TURNER
BY
Thos. Donnelly
ATTORNEY.

UNITED STATES PATENT OFFICE

ROBERT W. TURNER, OF DETROIT, MICHIGAN

FILING CABINET

Application filed April 6, 1931. Serial No. 528,057.

My invention relates to a new and useful improvement in a filing cabinet and has for its object the provision of a filing cabinet in which a maximum depth of drawer or 5 container may be provided in a casing possessing a minimum depth.

Another object of the invention is the provision in a filing cabinet of a plurality of filing drawers supported in a supporting 10 frame in overlapping relation and throughout the major portion of their body inclined to the casing and arranged with their outer ends in such a manner as to form a planal front for the casing.

15 Another object of the invention is the provision of a filing cabinet which is compact.

Other objects will appear hereinafter.

The invention consists in the combination 20 and arrangement of parts hereinafter described and claimed.

The invention will be best understood by a reference to the accompanying drawing which forms a part of this specification, and 25 in which,

Fig. 1 is a perspective view of the invention.

Fig. 2 is a sectional view taken on line 2-2 of Fig. 1.

30 Fig. 3 is a view taken on line 3-3 of Fig. 1.

Fig. 4 is a perspective view of one of the drawers.

35 Fig. 5 is a fragmentary sectional view of the supporting casing.

I provide a supporting frame or casing embodying the side walls 8 and 9 connected with the bottom walls 10 and 11 and supporting the back 12. Mounted on the inner 40 surface of each of the side walls 8 and 9 inclined to the longitudinal length thereof and in spaced relation are the guide strips 13. The filing drawers consist of the front wall 14 having its upper end 15 angularly turned. Projecting outwardly in spaced relation from the inner surface of this front wall at opposite sides thereof and inwardly 45 from the marginal edges of the front wall are the drawer side walls 16 connected at their lower or inner ends by the plate 17 and

the bottom 18, thus providing a compartment in which papers and other similar articles may repose.

In use, the drawers are slid into the supporting frame as illustrated, the portion 14 serving as flanges which engage the upper surface of the guide strips 13 and the bottom 18 engaging the supporting rails 20 which are mounted on the rear wall 12. As 55 clearly appears in the drawing, these drawers when mounted in the frame are projected inwardly of the frame diagonally thereto in overlapping relation to each other, and the angularly turned portion 15 of the front 60 wall of the drawers serves to form a front 65 for the filing cabinet thus formed, this front being substantially a planal one, the main portion of the wall 14 terminating and the portion 15 beginning at the edge of the portion 15 of the next lower drawer.

70 By constructing a filing cabinet in this manner, the depth of the supporting frame is reduced to a minimum and the length of the drawers in which the papers or documents are filed may be as desired.

75 It is obvious that in order to mount drawers of various lengths in a supporting frame, the inclination of the guide strips 13 vary. It is also believed obvious that the structure is one which is quite compact.

80 In Fig. 1 I have illustrated a section of a filing cabinet constructed so as to embody the invention, and it is believed obvious that the supporting frames may be of various sizes and that the same may be placed along 85 side of each other to provide such filing space as may be necessary.

While I have illustrated and described the preferred form of construction of my invention, I do not wish to limit myself to the precise details of structure shown, but desire to avail myself of such variations and modifications as may come within the scope 90 of the appended claims.

95 Having thus described my invention, what I claim as new and desire to secure by Letters Patent is:

1. In a filing cabinet of the class described, a vertically directed supporting frame; a plurality of drawers slidably 100

mounted on said supporting frame said drawers being inclined downwardly to the vertical and inwardly of the frame and having the outer ends thereof directed to extend 5 in a vertical position.

2. In a filing cabinet of the class described, a vertically directed supporting frame; a plurality of drawers slidably mounted on said supporting frame said 10 drawers being inclined downwardly to the vertical and inwardly of the frame and having the outer ends thereof directed to extend in a vertical position, the outer ends of successive drawers forming a planal front.

15 3. A filing cabinet of the class described comprising: a supporting frame having vertically extending side walls; spaced guide strips on said side walls inclined inwardly, downwardly to the vertical; a plurality of 20 drawers each slidably mounted on a pair of said guide strips, one of the walls of said drawers being, at one end, angularly turned to extend vertically while in engagement with said guide strips for forming with the 25 angularly turned ends of successive drawers a planal front on said frame.

4. A filing cabinet of the class described comprising: a supporting frame, having vertically extending side walls; guide strips 30 on the inner surface of each of said side walls in spaced relation and projecting diagonally downwardly; a rear wall on said frame; abutment strips on the rear wall of said frame, each in alignment with the inwardly directed ends of a pair of guide strips; a drawer slidably mounted on said strips and engaging at its inner end one of 35 said abutments, one of the walls of said drawers being angularly turned to extend, upon engagement of the drawer with its 40 abutment, parallel to the rear wall and form with the similar angularly turned end of other drawers a planal front for said frame.

In testimony whereof I have signed the 45 foregoing specification.

ROBERT W. TURNER.
